LOCK

Maurice Samburg, Brooklyn, N. Y., assignor to
 Lock Patents Holding Corporation, New York,
 N. Y., a corporation of New York

Application August 10, 1929. Serial No. 384,983

26 Claims. (Cl. 70—113)

This invention relates to locks, such as combination controlled padlocks, and the like articles.

An object of this invention is to provide a lock of the character described, having means for operating the combination controlled mechanism for opening the lock either with or without the combination numbers being visible.

Another object of this invention is to provide a lock of the character described having improved means for changing the combination for said lock.

A further object of this invention is to provide a lock of the character described which may be closed regardless of the position of the combination controlled mechanism.

A still further object of this invention is to provide a lock of the character described wherein the proper combination for opening the lock may be easily set by sense of touch or hearing and without necessitating observation of the numbers or other markings on the combination control mechanism.

Still another object of this invention is to provide a device of the character described which shall be relatively inexpensive to manufacture, comprise few and simple parts, easy to manipulate and which shall yet be positive in operation and practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention:

Fig. 1 is a front elevational view of a lock embodying the invention.

Fig. 2 is an elevational view of the lock, with the lock casing in cross section to show the interior construction.

Fig. 3 is a cross sectional view taken on line 3—3 of Fig. 5.

Fig. 4 is a cross sectional view taken on line 4—4 of Fig. 2.

Fig. 5 is a fragmentary end view of the combination controlled mechanism with parts broken away to show the interior construction.

Fig. 6 is a cross sectional view taken on line 6—6 of Fig. 2.

Fig. 7 is a cross sectional view taken on line 7—7 of Fig. 6; and

Fig. 8 is a rear view of the front plate of the lock casing.

Referring now in detail to the drawing, 10 designates a lock made in accordance with the invention herein shown in the form of a padlock 60 comprising a casing 11, a U shaped member or bolt 12 associated therewith in the manner hereinafter appearing, and combination controlled mechanism 14 within the casing for controlling the movements of said U shaped member. The 65 casing 11 comprises an annular wall 15, preferably having a pair of parallel bosses 16 and 17 projecting therefrom at one side thereof, a rear wall 18 and a front wall 19. One boss 17 may be provided with a relatively short vertical cylindrical bore 20, forming a bottom wall 21. The other boss 16 may be provided with a vertical cylindrical bore 22 equal in diameter to that of bore 20 but extending into the lower portion 23 of the casing wall 15 and forming a bottom 75 wall 24.

The U shaped bolt member or shackle 12 is provided with a short arm 25 extending into said opening 20 and terminating short of the bottom wall 21. The second and longer arm 26 of said 80 U shaped member extends within the opening 22 and terminates adjacent the lower wall 24 formed by said opening. Said arm 26 is provided adjacent the outer end thereof with a reduced portion 28 having a flat face 29 on the inner side thereof, and forming a head 27 at the outer end of said bolt. Said arm is furthermore provided with a slot 30 on the inner side thereof providing a flat face 31 aligned with said face 29 and forming a lug portion 31a interposed between said reduced 90 portion 28 and said slot. The shoulder 32 formed by said reduced portion 28 may be cut away to provide an undercut ramped surface 33 as shown in Figs. 2 and 7 of the drawing. A portion of the lug 31—a may be cut away as shown at 35 to provide a surface aligned with and interconnecting said flat faces 29 and 31. Thus, looking at Fig. 7 of the drawing, it is seen that the lug 31—a extends to the middle of the arm 26 to provide a radially extending vertical wall 36 transverse 100 to wall 35.

The combination controlled mechanism 14 within the casing 11 is provided with means for controlling the movement of the bolt 12. To this end, a plate 40 is attached to the rear wall 18 105 of the casing in any suitable manner, said plate having a portion 41 extending at right angles to said rear wall and adjacent and parallel to the opening 22 in said casing.

A second wall 42 parallel to said wall portion 110

41 is fixedly mounted within said casing in any suitable manner and is disposed substantially in a plane passing through the axis of opening 20. Fixedly secured to the wall 41 in any suitable manner, is a cylindrical sleeve 43 extending transversely of said lock casing and having an axis in the plane of the axes of said openings 20 and 22.

Said sleeve 43 preferably terminates short of the wall 42 for the purpose hereinafter appearing. Rotatably and slidably mounted within said sleeve 43 is a shaft or bolt 44 having a portion 45 extending through an opening in wall 41 and normally projecting through said wall and terminating adjacent the flat faces 29, 35 and 31. Said end portion 45 of the shaft 44 is formed with an edge portion 46 having a flat face 47 extending longitudinally of said shaft and with a ramped cammed or curved outer face 48. As shown in Fig. 6 of the drawing, said edge is adapted to extend longitudinally of arm 26 of bolt 12 and projects into the cutout portion 35 of the collar 31—a when the lock is in open position, thus permitting the bolt 12 to be drawn upwardly to disengage the arm 25 from the opening 20.

The bolt 12 may be drawn outwardly from the position shown on Fig. 2, until the collar 27 of the arm 26 strikes the under side of the shaft end 45, thus preventing complete removal of the bolt from the lock. However, upon drawing the bolt 12 upwardly, because of disengagement of the arm 25 from opening 20, said bolt may be pivoted about said arm 26 to disalign said arm 25 from said opening to permit removal of the padlock from the latch or closure to which it may be attached. This pivotal movement is permitted since the end portion 45 of the shaft 44 will extend into the groove formed by the reduced portion 28.

Means is provided for turning the shaft 44 into locking position to prevent outward movement of the bolt 12, said means comprising a wheel 50 splined or keyed to said shaft in any suitable manner. Said wheel is preferably disposed parallel and adjacent to said wall 42 and is formed with a knurled outer surface 51 to facilitate actuation thereof. Said wheel may furthermore be provided with a pair of markings 52 such as arrows, spaced 90 degrees from each other to indicate the opening and closing positions of said shaft and the direction of movement of the wheel from one of said positions to the other.

As shown in Fig. 2, the shaft is in open position to permit removal of the bolt 12. A small coil compression spring 53 mounted in a socket 54 at one end of shaft 44 is adapted to press against the outer wall 15 of the casing to normally retain said shaft pressed in the position shown in Fig. 2. A flanged head or collar portion 54—a limits the movement of the shaft in the direction toward said arm 26. Thus, should the bolt 12 be withdrawn into the opening position and the shaft 44 thereafter actuated to closing position, so that the ramped surface 48 faces upwardly and extends beneath the collar 31—a, downward pressure of the bolt will cause said collar or shoulder 32 or ramped portion 33 to engage said ramped surface 48 and move the shaft to the right as shown in Fig. 2, against the pressure of spring 53, until the bolt is pressed inwardly and the edge portion 46 of the shaft again clears the collar 31 and snaps into groove 30 for closing the bolt. With this construction the bolt may be closed regardless of the position of shaft 44.

The wall 42 is formed with a cut-out portion

to provide an abutment 55 and a second abutment 56 at right angles to said first abutment. A small set screw 57 threaded into an opening 58 in the bottom wall 21 of the wall 17, extends downwardly and is provided with a portion 59 parallel to and somewhat spaced from said abutment 56. A pin 60 projecting from the side of wheel 50 is adapted to abut the horizontal abutment 55 when the shaft 44 is in lock opening position and to abut the extension 59 of member 57 when said shaft is in locking position.

Means is provided for controlling the movements of the shaft 44 and wheel 50 so that the latter may be turned to open position only when the combination control mechanism 14 is set to a predetermined combination of numbers. To this end a plurality of bushings 62 are rotatably mounted on the sleeve 43. For the purpose of illustration, only three such bushings are shown for a three number combination system. Obviously, however, any number of bushings for forming any number of combination numbers may be provided. Each of said bushings 62 is provided with a sleeve portion 63 contacting the outer surface of sleeve 43, and an outwardly extending flange 64 having a radial notch 65 formed therein. For the purpose hereinafter appearing, the sleeve 63 is formed with a longitudinal curved notch or keyway 66, and the sleeve 43 is formed with an elongated groove or slot 67 substantially equal to the width of said notch. Slidably mounted on the outer surface of each of said sleeve portions 63 is an indicator 70 having an outwardly extending flange portion 71 overlying the outer surface of said flange 64. Said indicator 70 is formed with a reduced portion 73 having spaced markings thereon such as the ten digits 73—a.

The flange 71 is preferably formed with notches 74 extending between each pair of adjacent digits and the portions 75 of said flange between said notches may be knurled, as at 76, to permit easy manipulation of said indicators. Each of said indicators 70 is formed with a countersunk portion 77 forming a wall 78 adapted to contact the inner surface of the flange 64 of bushing 62. A series of sockets 80 are formed on said inner wall 78, there being one socket aligned with each digit 73—a. Thus, in the illustrated form ten sockets are formed equally spaced along said annular wall 78. The sockets are shaped to form a portion of a sphere for receiving a portion of a ball 81 mounted within said notch 65.

It will now be understood that the ball 81 interconnects or splines each bushing 62 with its respective indicator 70 to prevent relative rotation therebetween.

An elongated pin 85 extends within the slot 67 formed in the sleeve 43, said pin having a diameter slightly greater than the width of said sleeve, and hence partially extending into the notches 66 formed in the bushings 62 when all of said notches are aligned with said slot 67.

The shaft 44 is likewise formed with an elongated longitudinal notch or groove 86 substantially similar in cross-sectional shape to the notch 66 so that when said shaft is turned to align said notch 86 with groove 67, the pin 85 will drop to permit the lower portion thereof to lie within said notch 86. When the pin has thus dropped to this position the bushings may be turned by rotating the indicators 70. It will now be understood that unless the bushings 62 are in position for aligning all of the notches 66 with the groove 67, movement of the shaft 44 cannot take place since the pin 85 partially extends into the notch 86.

and hence locks or splines the shaft 44 to the fixed sleeve 43.

It will furthermore be understood that it is necessary to rotate the indicators 70 to a predetermined position for bringing a predetermined combination of numbers to the front of the casing to the position shown at 88 for bringing the bushings 62 into the position of aligning the notches 66 with the slot 67 and hence permit rotation of the shaft 44 to the opening position shown in Fig. 2. The number to which the indicators are to be turned, depends, obviously, upon the relative position of each bushing with respect to its indicator. This relative position depends upon the socket 80 into which the ball 81 projects. As illustrated in the drawing, there are three indicators and three bushings shown so that all three indicators will have to be moved by actuating the knurled flanges 71 to bring a combination of three numbers into view at the front of the casing for correctly positioning the bushing as above described.

Washers 89 may be fixedly interposed between adjacent pairs of bushings 62, said washers likewise being provided with notches similar to notches 66 and aligned with groove 67. Thus, when the proper combination of numbers is set the wheel 50 may be turned to the position shown in Figs. 2 and 3 and the bolt 12 thereafter drawn outwardly and pivoted about arm 26 thereof to open the lock. For closing the lock it is merely necessary to align arm 25 of said bolt 12 with opening 20, push the bolt back into closing position, move the wheel 50 back into closing position, as indicated, and then rotate one or all of the indicators 70 to disalign the notches 66 with the groove 67, thus forcing or permitting the pin 85 to drop down into the notch 86 in said shaft 44 to lock said shaft to the fixed sleeve 43. With the indicators upset, the lock cannot be opened by one who does not know the combination. It will be noted that once the relative positions between the bushings 62 and their respective indicators 70 have been determined by the positions of said balls 81, the combination cannot be changed unless such relative positions are changed. Should it be desired to prevent change of the combination after the lock has been assembled, it is merely necessary to provide means for permitting no longitudinal relative movement between the bushings and their respective indicators thereby retaining said members permanently interlocked, or the two members may be made in one piece.

Means is provided, however, for changing the combination to be set for permitting opening of the lock. To this end a washer 90 is slidably and non-rotatably mounted on the sleeve 43 at one end 91 thereof. The outer face 92 of said washer is provided with a plurality of preferably equiangularly spaced notches 93, for instance three in number, and the adjacent face 94 of the wheel 50 is likewise formed with the same number of complementary sockets 95, each complementary pair of sockets substantially receiving half of a small spherical ball 96. Thus when the sockets 95 are aligned with sockets 93 the washer 90 may be longitudinally moved toward the face 94 of the wheel 50. This aligned position of the sockets may be accomplished by setting the proper combination for opening the lock and unscrewing the screw member 57 to lift the end portion of 59 out of the path of the pin 60 projecting from one face of said wheel 50. When this operation is effected the wheel 50 may be turned a small angle beyond the

position shown in Fig. 4 of the drawing, so that the pin will contact the abutment wall 56 and bring the complementary sockets into alignment. This operation locks the bushings against rotary movement and permits relative longitudinal movement between each pair of complementary bushings 62 and indicator 70 as shown in Fig. 5 of the drawing. This relative movement may be effected by rotating the indicators, such rotation causing sliding movement thereof to the right and moving the washer 90 toward wheel 50. Rotation of an indicator 70 will dislodge the ball 81 from the socket 80 into which it had projected and bring the ball into alignment with another socket 80. Thus each indicator may be moved selectively to bring a new number or digit 73—a into the position shown at 88, and hence a new combination of numbers is provided.

It will be noted that only one indicator may be rotated at a time to change the combination. After a combination has been changed, rotation of the wheel 50 back to the position shown in Fig. 4 will cause disalignment of the sockets 93 with the sockets 95 and hence balls 96 will be dislodged from sockets 95 and roll up on the face 94 of the wheel 50, thus pushing the washer 90 toward the left and locking of complementary bushings and indicators to one another. The screw 57 may then again be screwed to bring the end 59 thereof down into the path of pin 60. The operation of the lock will then be the same as described above, except that the new combination of numbers must be set to bring the lock into position for permitting actuation of the shaft to opening position.

As shown in Fig. 1, the front face 19 of the casing 11 is provided with a slot 100 through which a portion of the wheel 50 extends to permit actuation of said wheel from the outside of the casing. Said plate is furthermore provided with three T shaped slots 101 through which knurled portions 76 of the indicator 70 extend to permit finger actuation of said indicators, and also to permit observation of the number or digit 73—a on each indicator at the position designated at 88 at the front of the casing.

Means is provided to permit setting of the combination to opening position without exposing the numbers set on the indicators, so that the lock may be opened without disclosing the combination to a bystander.

To this end, plate 19 is formed with a small slot 102 adjacent to the upper end thereof and with a pin 103 adjacent the lower end thereof aligned with said slot 102, and extending into said casing 11. Slidably mounted on the rear face 19—a of said plate 19 is a plate 104 having an extension 105 provided with a transverse pin 106 extending through said slot 102. Said pin 106 is preferably provided with a head 107 contacting the outer surface of said plate 19. Said plate 104 may furthermore be formed with an extension 108 provided with a slot 109 receiving said pin 103. It will now be understood that the plate 104 may be moved up or down. A small coil spring 110 mounted on a pin 111 projecting from the inner surface 19—a of said plate 19, is formed with an arm 112 engaging the underside of said pin 106 and with another arm contacting a fixed abutment 113 for normally maintaining said plate 104 in raised position. Said plate is provided with a slot 115 registering with slot 100 but somewhat longer than said slot to permit the sliding movement of said plate 104. Likewise said plate is formed with three T shaped slots 116 registering with said slots 101. Each

of said slots 116 is formed, however, with a vertical portion 117 somewhat longer than the slot 101 to permit up and down movement of the plate. Each of said slots 116 is also provided with a portion 118 adapted to expose to view the digits 73—a at the front position on said indicators. It will be noted, however, that normally, due to the action of spring 112, the plate will be raised and the portion 119 of said plate adjacent the opening 118 will be moved upwardly to cover the indicator numbers at position 88. Should the operator wish to see the numbers on the indicator it is merely necessary to press downward on the head 107 of the pin 106, the plate 104 thereby being moved downwardly against the tension of the spring 112 to uncover the combination numbers.

To permit operation of the combination without uncovering the plate 104, a plate 120 secured to said wall 40 is provided with three projecting spring fingers 121, each resiliently pressing downwardly against the outer flange 71 of the indicators. Thus upon moving each indicator, the spring fingers 121 will press downwardly and snap into the successive notches 74. Preferably one notch in each of the indicators is formed with a hook portion 123 adapted to abut the bent end portion 124 of each spring and limit the clockwise movement of the indicator as shown in Fig. 3 of the drawing. The notch provided with this hook or abutment portion 123 is preferably such that when said notch engages said end portion 124 the digit 0 will show at the front of the casing. Thus, without looking at the numbers, the operator may first rotate the indicators clockwise to bring the indicators to 0—0—0 position, this position being indicated when said clockwise rotation is stopped by contact of the spring end 124 with the neck portion 123. Each indicator may then be moved in a counter-clockwise direction to bring the indicators to the proper position for opening the lock. In moving the indicators in a counterclockwise direction, the operator may feel or hear the spring end 124 snap into each notch 74 and may hence count the number of sounds or pulsations due to such action of the springs. Thus the operator by counting the pulsations may bring the indicators to the proper position depending upon the number to be set for each indicator.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth or shown in the accompanying drawing is to be interpreted as illustrative and not in a limiting sense.

Having thus described my invention, what I claim as new and desire to secure by Letters Patent, is:—

1. In a lock, in combination, a casing, a bolt, combination controlled mechanism within said casing for locking said bolt to said casing, said casing having an opening therein to permit viewing the combination markings therethrough, a member movably mounted on said casing for covering said opening, and resilient means for normally retaining said member in covering position.

2. A lock comprising a casing, a bolt and combination controlled mechanism in said casing for

locking said bolt to said casing, said casing being provided with a front face having an opening therein, said mechanism including an annular member mounted for rotation in a plane transverse to said face, said member having a peripheral portion protruding through said opening to permit finger actuation thereof and a portion having markings thereon entirely housed within said casing, said markings being viewable through said opening and a member interposed between said marked portion and face to cover said opening and prevent viewing of said markings, said last named member having an opening receiving said peripheral portion therein.

3. A lock comprising a casing, a bolt, and combination controlled mechanism in said casing for locking said bolt to said casing, said mechanism comprising a sleeve fixed within said casing, a shaft rotatably mounted within said sleeve, having means for releasably engaging a portion of said bolt, means for locking said shaft to said sleeve, said last mentioned means comprising a member rotatably mounted on said sleeve, means for locking said member to said sleeve, a member rotatably mounted on said first member, and means for locking said members against relative rotation.

4. A lock comprising a casing, a bolt, and combination controlled mechanism in said casing for locking said bolt to said casing, said mechanism comprising a sleeve fixed within said casing, a shaft rotatably mounted within said sleeve having means for releasably engaging a portion of said bolt, means for locking said shaft to said sleeve, said last mentioned means comprising a member rotatably mounted on said sleeve means for locking said member to said sleeve, a member rotatably mounted on said first member, means for locking said members against relative rotation, and means for locking said members against relative longitudinal movement.

5. A lock comprising a casing, a bolt, and combination controlled mechanism in said casing for locking said bolt to said casing, said mechanism comprising a sleeve fixed within said casing, a shaft rotatably mounted within said sleeve having means for engaging a portion of said bolt, means for locking said shaft to said sleeve, said last mentioned means comprising a member rotatably mounted on said sleeve, means for locking said member to said sleeve, a member rotatably mounted on said first mentioned member, means for locking said members against relative rotation, means for locking said members against relative longitudinal movement, and means for releasing said locking means.

6. In a lock, in combination, a casing, a substantially U-shaped bolt having arms of unequal length projecting into said casing, means cooperating with said longer arm for locking the same against outward movement, combination controlled means for releasing said locking means to permit such outward movement, said bolt being swingable on said casing about the longer arm of said bolt, and means for preventing complete removal of said bolt from said casing, said means being adapted to permit return inward movement of said bolt in all positions of said locking means.

7. In a lock, in combination, a fixed sleeve, a member rotatably mounted on said sleeve, and an annular member mounted on said first member, said first member having an opening, said annular member having a socket, and a member received in said opening adapted to project into said socket.

8. In a lock, in combination, a fixed sleeve, a member rotatably mounted on said sleeve, an annular member mounted on said first member, said first member having an opening, said annular member having a socket, and a member received in said opening to project into said socket, and means for locking said first member to said sleeve. 5 80
9. In a lock, in combination, a fixed sleeve, a member rotatably mounted on said sleeve, an annular member mounted on said first member, said first member having an opening, said annular member having a socket, a member received in said opening adapted to project into said socket, means for locking said first member to said sleeve, and means for locking said first member and annular member against longitudinal relative movement. 10 85
10. In a lock in combination a fixed sleeve, a member rotatably mounted on said sleeve, an annular member mounted on said first member, said first member having an opening, said member having a socket, and a member received in said opening adapted to project into said socket, means for locking said first member to said sleeve, means for locking said first named member and annular member against relative longitudinal movement, and means for releasing said locking means. 20 90
11. In a lock, in combination, a fixed sleeve, a member rotatable thereon, an annular member rotatably mounted on said sleeve, means for locking said members against rotary movement, means for locking said members against relative longitudinal movement, and means for releasing said last named means. 30 95
12. In a lock, in combination, a fixed sleeve, a member rotatable thereon, an annular member disposed about and rotatable with respect to said sleeve, means for locking said members together in a plurality of relative angular positions, means for locking said members against relative longitudinal movement, and means for releasing said locking means. 40 100
13. In a lock, in combination, a casing, a bolt extending into said casing, a fixed sleeve in said casing, a shaft rotatably mounted in said sleeve and disposed transversely of said bolt, resilient means for longitudinally moving said shaft toward said bolt, and combination controlled means for governing rotation of said shaft. 45 105
14. In a lock, combination controlled mechanism, comprising a fixed sleeve, a plurality of annular members mounted on said sleeve, a plurality of indicator wheels mounted on said members respectively, and means for selectively locking said wheels to said members in a plurality of angular positions, said means comprising means for locking said members and wheels against relative longitudinal movement and means for releasing said locking means. 55 110
15. In a lock, combination controlled mechanism, comprising a fixed sleeve, a plurality of annular members mounted on said sleeve, a plurality of indicator wheels mounted on said members respectively, and means for selectively locking said wheels to said members in a plurality of angular positions, said last named means including means for permitting relative rotary movement between only one member and its wheel at a time. 60 115
16. In a lock, combination controlled mechanism comprising a cylindrical member, a plurality of annular members mounted on said first member, a wheel having indicating means, 70 120
- mounted on each of said annular members, and means for permitting relative rotary movement between only one of said annular members and its wheel at a time. 75 125
17. In a lock, combination controlled mechanism comprising a sleeve, a plurality of annular members mounted on said sleeve, a wheel having indicating means, mounted on each of said members, and means for preventing simultaneous relative rotation between said members and wheels. 80 130
18. In a lock, a casing, a U-shaped bolt slidably extending into said casing, and a shaft rotatably and slidably mounted in said casing adapted to cooperate with said bolt for locking the same to said casing in one angular position of said shaft, and release said bolt in another angular position of said shaft and means for causing sliding movement of said shaft. 85 135
19. In a lock, a casing, a U-shaped bolt slidably extending into said casing, a shaft rotatably and slidably mounted in said casing adapted to cooperate with said bolt for locking the same to said casing in one angular position of said shaft, and release said bolt in another angular position of said shaft, combination controlled mechanism for governing rotation of said shaft and means for causing sliding movement of said shaft. 90 140
20. In a lock, in combination, a casing, a bolt, combination controlled mechanism within said casing for locking said bolt to said casing, said casing having an opening therein to permit viewing the combination markings therethrough, a member movably mounted on said casing for covering said opening, resilient means for normally retaining said member in covering position, and a handle on said member protruding from said casing for moving said member to uncovering position. 100 145
21. A lock comprising a casing, a bolt having a portion slidably received within said casing, and combination controlled mechanism in said casing for locking said bolt, said mechanism comprising a sleeve fixed within said casing, a shaft slidably and rotatably mounted within said sleeve and disposed at right angles to said portion, said shaft having an end portion adapted to engage said portion of said bolt, and means forming part of said mechanism, for locking said shaft to said sleeve, said shaft being movable to release said bolt to permit sliding movement of said portion. 110 150
22. A lock comprising a casing, a substantially U-shaped bolt having an arm slidably and rotatably received in said casing, and combination controlled mechanism in said casing for locking said bolt, said mechanism comprising a sleeve fixed within said casing, a shaft rotatably and slidably mounted within said sleeve and disposed in the plane of said bolt, and transversely of said arm, said shaft having a portion adapted to engage said bolt, and means forming part of said mechanism for locking said shaft to said sleeve in bolt engaging position. 120 155
23. A lock comprising a casing, a substantially U-shaped bolt having a long arm and a short arm, said long arm being slidably and rotatably received in said casing, and said short arm being slidably received in said casing, and combination controlled mechanism in said casing for locking said bolt to said casing, said mechanism comprising a sleeve fixed within said casing, a shaft rotatably mounted within said sleeve and disposed transversely of said long arm, said 130 160
- 140
- 145
- 150

shaft having an end portion adapted to engage said long arm in one angular position of said shaft and to release said bolt in another angular position of said shaft to permit sliding movement of the latter, and means forming part of said mechanism, for locking said shaft to said sleeve.

24. A lock comprising a casing, a substantially U-shaped bolt having an arm slidably received in said casing, and combination controlled mechanism in said casing for locking said bolt to said casing, said mechanism comprising a sleeve fixed within said casing, a shaft rotatably mounted within said sleeve having means for engaging said arm in one angular position of said shaft, and adapted to release said bolt in another angular position thereof to permit sliding movement of said arm, and means forming part of said mechanism, for locking said shaft to said sleeve.

25. A lock casing, a bolt having a portion slidably mounted in said casing, and combination controlled mechanism in said casing for locking said bolt to said casing, said mechanism comprising a sleeve fixed within said casing, a shaft mounted within said sleeve and disposed transversely of said portion of said bolt, said shaft having an end portion engaging said portion of

said bolt in one angular position thereof, and being adapted to release said bolt in another angular position thereof, to permit sliding movement of said portion, and means forming part of said mechanism, for locking said shaft to said sleeve, said last mentioned means comprising a member rotatably mounted on said sleeve.

26. A lock comprising a casing, a substantially U-shaped bolt having a long arm rotatably and slidably mounted within said casing, and a short arm, slidably received within said casing, and combination controlled mechanism in said casing for locking said bolt to said casing, said mechanism comprising a sleeve fixed within said casing, a shaft rotatably mounted within said sleeve, said shaft being disposed at right angles to said longer arm and having an end portion engaging said arm in one position of said shaft to prevent sliding movement of said bolt, said shaft being adapted in another angular position thereof to release said bolt to permit sliding movement thereof, and means forming part of said mechanism, for locking said shaft to said sleeve, said last mentioned means comprising a member rotatably mounted on said sleeve, and means for locking said member to said sleeve.
